DECORATIVE RAILING CAP

Norman B. Huret, Wadsworth, Ohio, assignor to Locke Manufacturing Company, Lodi, Ohio, a corporation of Ohio

Filed Dec. 20, 1962, Ser. No. 72,917

Term of patent 14 years

(Cl. D13—7)

FIG. 1

FIG. 2

FIG. 3

FIGURE 1 is a perspective view of a decorative railing cap partially broken away to indicate an indeterminate length showing my new design.

FIGURE 2 is a side elevation thereof partially broken away to indicate an indeterminate length.

FIGURE 3 is an end elevation thereof.

I claim:

The ornamental design for a decorative railing cap, as shown and described.
